Des. 240,714
Patented July 27, 1976

240,714

FOOD PACKAGING TRAY

Thomas H. White, Statesville, N.C., assignor to Rubbermaid Industrial Products Corporation, Statesville, N.C.

Filed Mar. 3, 1975, Ser. No. 554,757

Term of patent 14 years

Int. Cl. D9—03

U.S. Cl. D9—219

FIG. 1

FIG. 2

FIG. 4

FIG. 5

FIG. 6

FIG. 1 is a top plan view of a food packaging tray embodying my new design.

FIG. 2 is a side elevation thereof, the opposite side being identical.

FIG. 3 is an end elevation thereof, the opposite end being identical.

FIG. 4 is a bottom plan view thereof.

FIG. 5 is a partial sectional view on an enlarged scale on line 5—5 of FIG. 4.

FIG. 6 is a partial sectional view on an enlarged scale partly broken away, on line 6—6 of FIG. 4.

I claim:

The ornamental design for a food packaging tray, as shown and described.
